Inventor:

G. G. Townsend

United States Patent Office.

G. G. TOWNSEND, OF ROCHESTER, NEW YORK.

Letters Patent No. 75,602, dated March 17, 1868.

IMPROVED SHOE-KNIFE GUARD.

The Schedule referred to in these Letters Patent are making part of the same.

TO ALL WHOM IT MAY CONCERN:

Be it known that I, G. G. TOWNSEND, of Rochester, in the county of Monroe, and State of New York, have invented a new and useful "Shoe-Knife Guard;" and I do hereby declare that the following is a full, clear, and exact description thereof, reference being had to the accompanying drawings, making part of this specification, in which—

Figure 1 is a top view of my invention as applied to the blade of the ordinary trimming-knife.

Figure 2 is a view of the back of the same.

Like letters indicate corresponding parts.

The nature of this invention consists in the employment of an adjustable skeleton-guard, which, may be applied to any ordinary trimming-knife for dressing the upper edge of boot and shoe-soles next to the uppers.

To enable others to make and use my invention, I will describe its construction and operation.

The guard is composed of the frame *f*, having the shank *s* and the spur *g*, which acts as a guide and guard to the cutting-point of the knife. The outer face of this spur is made slightly oval, as shown at *a*, fig. 2, and is provided on the opposite or inner face with a shallow V-shaped groove to receive the bevelled end of the blade *B* of the knife. The encircling-bar *b*, shown mostly by dotted lines in fig. 1, is cast to the frame *f* by offsets, as shown at *d*, fig. 2. The back bar of the frame is thickened, and is also offset, as shown, in order that the points of the clamping-screw *s'*, which is tapped through this ear or offset *h*, shall strike the back of the blade. This drives the end, which is cut off obliquely, of the blade at *e* firmly into the V-shaped groove, and thoroughly attaches it to the knife-blade *B*.

The guards may be made of steel, or of malleable iron, and case-hardened, rendering them very durable, and by making them of proper size to be applicable to a wide or a narrow blade, old worn blades may be converted into good trimming-knives by the application of the guard.

The great liability of cutting the uppers of boots and shoes by the makers, with the ordinary trimming-knives, is too well understood to require any explanation; but, by the employment of this guard, that serious difficulty is entirely obviated, and in an entirely perfect manner, as regards that part of the work.

What I claim as my invention, and desire to secure by Letters Patent of the United States, is—

The skeleton-guard *G* for shoemakers' trimming-knives, consisting of the lip *g*, shank *s*, frame *f*, and encircling-bar *b*, in combination with the binding-screw *s'*, substantially in the manner and for the purposes set forth.

G. G. TOWNSEND.
